UNITED STATES PATENT OFFICE.

GEORGE R. HUFF, OF SASAKWA, OKLAHOMA, ASSIGNOR OF ONE-FOURTH TO HARRY H. DIAMOND AND ONE-FOURTH TO CHARLES L. ORR, BOTH OF HOLDENVILLE, OKLAHOMA.

STEAM CYLINDER.

1,418,079.

Specification of Letters Patent. Patented May 30, 1922.

Application filed July 23, 1921. Serial No. 487,127.

To all whom it may concern:

Be it known that I, GEORGE R. HUFF, a citizen of the United States, residing at Sasakwa, in the county of Seminole and State of Oklahoma, have invented certain new and useful Improvements in Steam Cylinders, of which the following is a specification.

The present invention relates to new and useful improvements in steam engines and more particularly to a cylinder construction.

The primary object of the invention is the provision of means for controlling the intake and exhaust ports of an engine cylinder.

Another object of the invention is the provision of means actuated by the piston of a cylinder for controlling the intake and exhaust ports thereof.

Still another object of the invention is the provision of a slide valve actuated by the movement of the piston within the cylinder for controlling the flow of driving medium to and from the engine cylinder.

Another object of the invention is the provision of a steam engine cylinder which will be comparatively simple and inexpensive to manufacture, reliable and efficient in use, and readily operated.

With the above and other objects in view, the present invention resides in the novel features of construction, formations, combinations and arrangement of parts, to be hereinafter more fully described, claimed, and illustrated in the accompanying drawings forming a part of the present application in which:

Fig. 1 is an end view of a cylinder looking in the direction of the head;

Fig. 2 is a similar view looking toward the opposite end of the cylinder;

Fig. 3 is an end view of a piston;

Fig. 4 is a horizontal sectional view taken through the cylinder of the engine;

Fig. 5 is a detail view of the valve removed;

Fig. 6 is a longitudinal sectional view taken through the engine cylinder looking at the inner side of the valve;

Fig. 7 is a transverse sectional view taken on the line 7-7 of Fig. 4; and

Fig. 8 is a side elevation of the piston removed.

Referring to the accompanying drawings, 55 by suitable characters of reference through

out the several views, the numeral 10 denotes in general an engine cylinder mounted upon a suitable base 11 and closed at one end by an integral end 12, and at its opposite end by a removable head 13 provided with a stuffing box 14 through which the piston rod 15 operates. This piston rod 15 has attached to its inner end a piston 16 designed to operate in the usual manner within the cylinder 10.

The cylinder 10 is provided at its opposite ends with intake ports 17 and 17^a, while disposed inwardly thereof and adjacent thereto and in alignment therewith are exhaust ports 18 and 18^a. The intake pipes 19 connect with the ports 17 and 17^a while the exhaust ports 18 and 18^a are connected to the usual exhaust pipe 20 so that the fluid or driving medium can be supplied to the cylinder and likewise exhausted therefrom.

A slide valve 21 is mounted in guides 22 within the engine cylinder and includes a pair of plates 23 and 23^a connected by a spacing and guide rod 24.

The plates 23 and 23^a have inwardly projecting stops 25 and 25^a for a purpose to be later explained, while formed in the valves 23 and 23^a are openings 26 and 26^a adapted to register respectively with the ports 17 and 18, and 18^a and 17^a.

Pockets 27 and 27^a are formed in the adjacent side of the piston 16 for receiving the stops 25 and 25^a respectively, and allowing for the movements of the piston within said cylinder.

The pockets 27 and 27^a are separated by an abutment 28 designed to engage the stops 25 and 25^a upon movement of the piston 16 for actuating the valve.

The openings 26 and 26^a are so arranged that when the opening 26 is in registration with the exhaust port 18, the opening 26^a will be in registration with the intake port 17^a, and when the said opening 26 is in registration with the intake port 17, the opening 26^a will be in registration with the opening 18^a.

In operation, when the piston 16 moves to its outward limit of movement the driving medium can flow into the outer end of the cylinder through the intake port 17^a and opening 26^a in the plate 23^a, which obviously forces the piston 16 toward the opposite end of the cylinder allowing the exhausted driving means to flow out through 110

the exhaust port 18 and opening 26 formed in the plate 23.

As the piston 16 moves in the direction of the arrow shown in Fig. 4, the abutment 28 will engage the stop 25 moving the valve 21 so that the openings 26 will register with the intake port 17 and the opening 26^a, with the exhaust port 18^a permitting the driving fluid to flow in the cylinder beyond the opposite end of the piston reversing the moving of the latter.

This operation is continued until it is desired to stop the engine which can be accomplished in any simple and efficient manner.

From the foregoing description taken in connection with the accompanying drawing, it will be manifest that an engine is provided which will fulfill all of the necessary requirements of such a device, and it should be understood in this connection, that various minor changes in the specific details of construction can be resorted to within the scope of the appended claims without departing from the spirit or sacrificing any of the advantages of the invention.

Having thus described the invention, what I claim as new is:

1. In an engine, a cylinder having intake and exhaust ports therein, a piston operating in the cylinder, a valve slidably mounted

within the cylinder and controlling the intake and exhaust ports, said piston having pockets formed therein, stops formed upon the valve for sliding movement within the pockets, and an abutment formed upon the piston between the pockets for engagement with the stops and actuating the valve.

2. In an engine, a cylinder, a piston in said cylinder having pockets formed therein and an abutment between said pockets, guides formed within the cylinder, said cylinder having an intake and an exhaust port in each end thereof, a valve including spaced plates slidably mounted in said guides, said plates each having an opening therein for registration with the alternate exhaust and intake ports at each end of the cylinder, and stops extending from said plates in the path of said pockets for engagement with the abutment whereby the valve will operate to open and close the intake and exhaust ports alternately at the opposite ends of the cylinder upon movement of the piston in reversed direction.

In testimony whereof, I affix my signature in the presence of two witnesses.

GEORGE R. HUFF.
